DISPLAY TRAY

Michael Mordkin, Columbia, N.J.

Application January 24, 1949, Serial No. 72,520

5 Claims. (Cl. 220—4)

1

This invention relates to trays for the display of merchandise, such as shirts, and has for an object to provide a tray such that any two trays will fit together to form a closed storage box and such that the storage boxes may be stacked on top of each other without substantial interference of anti-friction runners on the trays. Other objects are inexpensiveness and simplicity of construction, neatness in appearance and ease and reliability of closure when combined into a storage box. Other objects and advantages of the invention will appear from the following particular description of one embodiment of the invention illustrated in the accompanying drawings, in which

Fig. 1 is a perspective of a tray embodying the invention.

Fig. 2 is a perspective, with a part in section, of a storage box composed of two of the trays.

Fig. 3 is a central longitudinal sectional elevation of a storage box with the component trays shown spaced, the plane of the section being indicated by line 3—3 in Fig. 2.

Fig. 4 is an enlarged sectional detail on plane of line 4—4 of Fig. 2.

Fig. 5 is a perspective showing three of the storage boxes stacked.

The trays are designed so as to be suitable for molding from a transparent plastic, such as styrene, and so that identical trays may be combined to make a closed box and so that the boxes may be stacked. The tray is shown as shallow, although its height may be suited to the character of the merchandise to be displayed.

As shown, the tray is of elongated, rectangular shape, its length from front to rear being greater than its width. It has a bottom 1, a front wall 2, a rear wall 3, and two similar side walls 4 and 5. The rear wall is substantially higher than the front wall, being shown as approximately two and one-half times as high. The side walls are shaped so that when they are put together edge to edge in inverted relation, they mutually serve as complements to form a rectangular side of a closed box. As shown, the height of the tray is maintained as the height of the front wall for the front third of the tray, and the rear third is maintained uniformly at the height of the rear wall, and the middle third is evenly inclined with its edge joining the top edges of the front and rear thirds. Thus, as shown in Figs. 2, 3 and 5, the edges of two trays in inverted relation will come together all around and make a closed box with its top and bottom parallel and with its ends and sides rectangular.

In order thus to make a closed box of two trays, it is evident that the tray which is used as the cover is inverted about a central transverse axis, so that the front and rear walls engage at each

2

end, and the edges of the corresponding sides come together. To effect an interlock, therefore, one end wall is provided with a pocket or slot and the other end wall with a tongue proportioned and located to fit in the pocket or slot of the coating tray when two trays are joined to make a box.

In the construction shown, the rear wall 3 is provided on its upper edge with a central, upstanding projection or tongue 6 and the front wall 2 is provided with the pocket or slot 7. This pocket is formed by making a central cut-out 8 in the wall for a sufficient distance down from the top and of the width of the tongue. The outside wall of the pocket consists of a strip 9 which extends across the cut-out and slightly overlaps the wall 2 on each edge of the pocket and is integral therewith; and the inside wall of the pocket is formed by two flange strips 10 which are integral with the wall 2 on the two respective edges of the pocket and overlap the cut-out 8 for a distance and leave the inside central part of the cut-out uncovered. Functionally the depth of the pocket needs be no more than the length of the tongue 6, but for appearance it is preferred to make the pocket and the strip 9 the full height of the wall 2, and the lower part of the pocket below that occupied by the tongue may serve as a price ticket holder, for example, since the wall is transparent.

Since the tongue and pocket are both in the plane of their respective walls, they will be in register when the trays are brought together in the reverse relation shown in Fig. 2, and the cover tray is thereby frictionally interlocked with its counterpart below.

It is desirable that display trays of this sort be provided with anti-friction strips on the bottom to reduce the area of contact with the surface on which the trays rest, and it has been customary to provide such trays with narrow flat rails or with half round rails. However, with boxes made up of two identical trays, as proposed by this invention, such rails would interfere with the stacking of the boxes one on another, as is required for storage and as is illustrated in Fig. 5. The rails cannot well rest one on another, particularly the half round rails, and consequently the successive boxes would have to be offset the full width of a rail.

In accordance with this invention, the trays are provided on their under sides with rails 11 running longitudinally and disposed equal distances from their respective edges. As illustrated, the rails are V-shape, which, as shown in Fig. 5, permits the boxes to be stacked with the off-set of the alternate trays but one-half the width of the base of the rails.

It is obvious that the number of interlocking tongues and slots may be more than one for each

end of a box and that the top edges of the side walls may be otherwise shaped and that various other modifications may be made in the construction shown in the drawings and above particularly described, within the principle and scope of the following claims.

What is claimed is:

1. A display tray of elongated rectangular shape having its rear end wall higher than its front end wall and having similar side walls with a front section of uniform height equal to that of the front end wall and a rear section of the same length as that of the front section and of uniform height equal to that of the rear end wall and an intermediate section having an inclined top edge joining those of the front and rear sections, one of the end walls having an upstanding tongue extension in the plane of the wall and the other end wall having a slot in the plane of the wall of the width of the tongue and in alignment therewith longitudinally of the tray.

2. A display tray of elongated rectangular shape having its rear end wall higher than its front end wall and having similar side walls with a front section of uniform height equal to that of the front end wall and a rear section of the same length as that of the front section and of uniform height equal to that of the rear end wall and an intermediate section having an inclined top edge joining those of the front and rear sections, the rear end wall having an upstanding tongue extension medially disposed on its top edge and the front end wall having a medial cut-out of the width of the tongue together with interior and exterior members overlapping the cut-out and forming a pocket in the plane of the wall proportioned to the tongue.

3. A display tray of elongated rectangular shape having its rear end wall higher than its front end wall and having similar side walls with a front section of uniform height equal to that of the front end wall and a rear section of the same length as that of the front section and of uniform height equal to that of the rear end wall and an intermediate section having an inclined top edge joining those of the front and rear sections, one of the end walls having an upstanding tongue extension in the plane of the wall and the other end wall having a slot in the plane of the wall of the width of the tongue and in alignment therewith longitudinally of the tray, and

a pair of V-shape runners formed on the under face of the bottom of the tray extending longitudinally of the tray and symmetrically disposed between the center line and the respective longitudinal sides.

4. A display tray of elongated rectangular shape having its rear end wall higher than its front end wall and having similar side walls with a front section of uniform height equal to that of the front end wall and a rear section of the same length as that of the front section and of uniform height equal to that of the rear end wall and an intermediate section having an inclined top edge joining those of the front and rear sections, the rear end wall having an upstanding tongue extension medially disposed on its top edge and the front end wall having a medial cut-out of the width of the tongue together with interior and exterior members overlapping the cut-out and forming a pocket in the plane of the wall proportioned to the tongue, and a pair of V-shape runners formed on the under face of the bottom of the tray extending longitudinally of the tray and symmetrically disposed between the center line and the respective longitudinal sides.

5. A storage box consisting of two identical parts, each part comprising a tray of elongated rectangular shape having its rear end wall higher than its front end wall and having similar side walls with their top edges coinciding at their front and rear ends, respectively, with the tops of the front and rear end walls, the rear end wall having an upstanding tongue extension medially disposed on its top edge and the front end wall having a medial cut-out of the width of the tongue together with interior and exterior members overlapping the cut-out and forming a pocket in the plane of the wall proportioned to the tongue, and a pair of V-shape runners formed on the outside face of the bottom of the tray extending longitudinally of the tray and symmetrically disposed between the center line and the respective longitudinal sides; the one part being disposed inversely upon the other part as a cover with the ends reversed and the edges tightly fitting and the tongue upon each part entered into the pocket of the other part.
